UNITED STATES PATENT OFFICE.

ABRAHAM B. GERBRAND, OF BUHLER, KANSAS.

MEANS FOR STRETCHING COVERING AROUND PULLEYS.

No. 874,182.

Specification of Letters Patent.

Patented Dec. 17, 1907.

Application filed April 23, 1907. Serial No. 369,822.

To all whom it may concern:

Be it known that I, ABRAHAM B. GERBRAND, citizen of the United States, residing at Buhler, in the county of Reno and State 5 of Kansas, have invented certain new and useful Improvements in Means for Stretching Covering Around Pulleys, of which the following is a specification.

This invention provides a mechanism by 10 means of which the covering of pulleys is greatly facilitated and time and labor saved, the machine being of such formation as to be adapted to pulleys of different diameter and varying in width, and whether the face is 15 straight or beveled, the machine operating equally well and serving to stretch the covering with any desired degree of tension and holding the covering until fastened.

For a full description of the invention and 20 the merits thereof and also to acquire a knowledge of the details of construction and the means for effecting the result, reference is to be had to the following description and accompanying drawings.

25 While the invention may be adapted to different forms and conditions by changes in the structure and minor details without departing from the spirit or essential features thereof, still the preferred embodiment is 30 shown in the accompanying drawings, in which:

Figure 1 is a perspective view of a machine embodying the invention showing its application. Fig. 2 is a central transverse section. Fig. 3 is a front view of an end portion of the machine, the near portion of the adjustable clamp member being broken away.

Corresponding and like parts are referred to in the following description and indicated 40 in all the views of the drawings by the same reference characters.

The machine comprises two frames which are relatively movable, the one adapted to be clamped to the pulley and the other to 45 firmly grip the covering, and means for positively moving the said frames whereby the covering is stretched around the pulley to the requisite tension and held in said position until firmly secured.

50 The frame designated as the pulley frame and adapted to be secured thereto, comprises a longitudinal bar 1 and side pieces 2, the latter being in the nature of standards and

projected from end portions of the longitudinal bar in parallel relation and either secured thereto or forming a part thereof, the former construction being preferred. The side pieces or standards 2 have extensions 3 projecting in the same direction and away from the plane of the standards and supporting a bar 4 having a central opening in which is mounted a set screw 5 designed to effect relative movement of the two frames. The clamp members are adjustable upon the longitudinal bar 1 and are provided in pairs, 65 each pair adapted to grip one side of the rim of the pulley 6 to be covered. The clamp members 7 are automatically adjustable so as to conform to the face of the pulley whether the same be straight or beveled. 70 In addition to this pivotal adjustment, the clamp members 7 are adjustable in the length of the bar 1 according to the width of the pulley to be covered so as to engage with edge portions of the face of the rim thereof. 75

The clamp members 7 are of U-form, the said members embracing opposite sides of the bar 1 and having inwardly extended projections 8 entered into longitudinal grooves 9 formed in opposite sides of the bar 1, 80 thereby serving to retain said members in place and forming pivots for the members to turn upon. The inner face of the horizontal portion of each clamp member 7 is curved in the length of the bar 1 to provide 85 an element for contact with said bar to sustain the clamping force when the clamp member is under tension, thereby relieving the projections 8 of the compressive strain which would otherwise tend either to bend 90 or break the same. The coöoperating clamp members 10 are slidable upon the bar 1, each consisting of a shank provided at one end with a cuff 11 to embrace the bar 1 provided at its opposite end with a laterally extended portion 12 in which is formed a threaded opening to receive a clamp screw 13 which is adapted to engage the inner face of the rim of the pulley, thereby gripping said rim between the part 7 and the clamp screw 13. 100 The laterally extended portions 12 face each other and result in bringing the clamp screws 13 opposite to the respective complementary clamp members 7. The frame for clamping the covering 14 comprises a bar 15 105 having end pieces 16 and these parts may be

of integral formation, or if separately formed, joined in any substantial way. It is preferred, however, to form the parts 15 and 16 of a single bar whose end portions are bent about at a right-angle in the same direction. The end pieces 16 are arranged to come alongside the inner faces of side pieces 2 and are pivoted to the latter at 17. Lugs 18 project inward from the end pieces 16 and are 10 formed with threaded openings in which are fitted set screws 19. A clamp bar 20 parallels the bar 15 and is adapted to grip the covering 14 by the action of the set screws 19, said covering being passed between the 15 bars 15 and 20. The clamp bar 20 is notched in its ends to receive the respective end pieces 16 thereby preventing relative displacement of the clamp bar while at the same time admitting of its movement 20 towards and from the bar 15 to clamp or release the covering 14 as may be desired. A pair of lugs 21 project upwardly from the clamp bar 20 and pivotally support a nut 22 which receives the set screw 5 and co-operates therewith to effect relative movement 25 of the two frames when placing the covering 14 under tension as when stitching the same about the pulley 6.

As indicated in Fig. 1, the pulley to be 30 covered has one end of the covering secured thereto, after which the machine is clamped to the pulley in the manner stated, the clamp members 7 being moved to engage with opposite sides of the outer face of the 35 pulley and the clamp screws 13 engaging with the inner face of opposite side portions of the pulley, the clamp screws being turned so as to firmly grip the pulley between them and the bars 7. The covering 14 is passed 40 between the bars 20 and 15 and after being stretched by hand, is clamped by turning up the set screws 19. It is noted that the pulley 6 is arranged so as to occupy a central position, thereby equalizing the strain throughout 45 the length of the machine. Upon operating the set screw 5 which may be turned either by a rod or other implement, the two frames are separated, or more properly speaking, the frame gripping the covering 50 is swung upon its pivots 17, thereby subjecting the covering to tension, and after the covering has been stretched to the required degree, it is made fast to the pulley either by rivets or any desired way. The set screw 5 is now backed so as to relax the tension 55 upon the covering and the set screws 19 are loosened so as to release the covering after which the clamp screws 13 are turned outward to release the machine which is moved 60 forward upon the pulley and the parts retightened preliminary to operating the set screw 5 for stretching another portion of the covering about the pulley, this operation being repeated until the pulley is completely 65 covered.

Having thus described the invention, what is claimed as new is:

1. A machine for stretching covering around pulleys, the same comprising relatively movable frames each provided with 70 clamp means, the one for attachment to the pulley and the other for gripping the covering and means for separating the said frames to subject the covering to tension.

2. A machine for stretching covering about 75 pulleys, the same comprising relatively movable frames, means applied to one of the frames for clamping a covering, adjustable clamping means applied to the other frame for securing the same to the pulley and adapting the machine to pulleys of different widths, and means for moving the two frames apart for 80 subjecting the covering to tension.

3. A machine for stretching covering about pulleys, the same comprising relatively movable frames, means for separating the frames to subject the covering to tension, means applied to one of the frames for gripping the covering, and clamp means applied to the other frame for securing the same 85 to the rim of the pulley, said clamp means embodying a self adjusting clamp member to automatically conform to the nature of the pulley whether straight or beveled.

4. A machine for stretching covering about pulleys, comprising co-operating relatively movable frames, one of said frames being provided with means for gripping the covering, and clamp means applied to the other frame, said clamp means comprising 100 pairs of adjustable clamps, each clamp formed of a self adjusting clamp member, and a complementary clamp member formed of a shank having a laterally extended end in which is fitted a clamp screw.

5. A machine for stretching covering about pulleys, comprising relatively movable frames, one of the frames provided with means for gripping the covering, means for separating said frames to subject the covering to tension, the other frame comprising a longitudinal bar having grooves in opposite sides, clamp members adjustable on the longitudinal bar and embracing opposite sides thereof and having inner projections to enter the grooves thereof to retain said clamp members in place and admit of their turning, and co-operating clamp members slideable upon said longitudinal bar and provided with clamp screws.

6. A machine for stretching covering about pulleys comprising two frames pivotally connected and each comprising a longitudinal bar, a set screw fitted to one of the frames, a nut having pivotal connection with the other frame and co-operating with said set screw, a clamp bar co-operating with the longitudinal bar of one of the frames, set screws moving said clamp bar to effect gripping of the covering, adjustable clamp mem- 120 125 130

bers fitted to the longitudinal bar of the other frame and having the sides in juxtaposition to said bar curved in the direction of the length thereof and complementary clamp

5 members slideable upon said longitudinal bar provided with clamp screws.

7. A machine for stretching covering about pulleys comprising a main frame, means for securing the main frame to a pulley, a swinging frame loosely mounted upon

the main frame, means carried by the swinging frame for engaging the covering, and means for moving the swinging frame to stretch the covering.

In testimony whereof I affix my signature 15 in presence of two witnesses.
